Primary Examiner — Manpreet S Matharu*Assistant Examiner* — Keith J Wilson(74) *Attorney, Agent, or Firm* — Bass, Berry & Sims, PLC(57) **CLAIM**

The ornamental design for an accordion nozzle, as shown and described.

DESCRIPTION

FIG. 1 is a perspective view of an accordion nozzle showing my new design, wherein the accordion nozzle is in a compressed state;

FIG. 2 is a side view thereof;

FIG. 3 is a top view thereof;

FIG. 4 is a bottom view thereof;

FIG. 5 is a perspective view of an accordion nozzle showing my new design, wherein the accordion nozzle is in an extended state;

FIG. 6 is a side view thereof;

FIG. 7 is a top view thereof;

FIG. 8 is a bottom view thereof; and,

FIG. 9 is an environmental view of the accordion nozzle in an extended state when the accordion nozzle is in use with a bottle container.

The broken lines used in FIGS. 1, 2, 4-6 and 8 represent portions of the accordion nozzle and form no part of the claimed design. The broken lines used in FIG. 9 are directed

(Continued)

to environment in addition to portions of the accordion nozzle; all broken lines shown form no part of the claimed design.

1 Claim, 9 Drawing Sheets
